US00D831117S

(12) **United States Design Patent** (10) Patent No.: **US D831,117 S**
(45) Date of Patent: **** Oct. 16, 2018**

(54) **DIGITAL SIGNAGE**

(71) Applicant: **LG ELECTRONICS INC.**, Seoul (KR)

(72) Inventors: **Sangwon Yoon**, Seoul (KR); **Yeojeong Choi**, Seoul (KR); **Hongseok Kim**, Seoul (KR)

(73) Assignee: **LG ELECTRONICS INC.**, Seoul (KR)

(**) Term: **15 Years**

(21) Appl. No.: **35/503,306**

(22) Filed: **Jan. 4, 2017**

(80) **Hague Agreement Data**

Int. Filing Date: **Jan. 4, 2017**

Int. Reg. No.: **DM/094177**

Int. Reg. Date: **Jan. 4, 2017**

Int. Reg. Pub. Date: **Jul. 7, 2017**

(30) **Foreign Application Priority Data**

Jul. 5, 2016 (KR) 30-2016-0032785
